No. 724,074.

PATENTED MAR. 31, 1903.

G. F. ALLEN.

PISTON ROD PACKING.

APPLICATION FILED MAY 19, 1902.

NO MODEL.

Fig. I.

UNITED STATES PATENT OFFICE.

GEORGE F. ALLEN, OF ST. LOUIS, MISSOURI, ASSIGNOR TO HOYT METAL COMPANY, OF ST. LOUIS, MISSOURI, A CORPORATION.

PISTON-ROD PACKING.

SPECIFICATION forming part of Letters Patent No. 724,074, dated March 31, 1903.

Application filed May 19, 1902. Serial No. 108,038. (No model.)

To all whom it may concern:

Be it known that I, GEORGE FRANKLIN ALLEN, a citizen of the United States, residing in the city of St. Louis, in the State of Missouri, have invented certain new and useful Improvements in Piston-Rod Packing, of which the following is a full, clear, and exact description, reference being had to the accompanying drawings, forming part of this specification.

My invention relates to a packing for piston-rods, the object of the invention being to provide a construction wherein the metal rings only will have bearing against the piston-rod and also whereby they are constantly held to the rod as a result of their configuration and bearing contact.

My invention consists in features of novelty hereinafter fully described, and pointed out in the claims.

Figure I is a longitudinal section of a piston-rod packing constructed in accordance with my invention. Fig. II is a cross-section taken on line II II, Fig. I. Fig. III is a perspective view of two of the mating intermediate packing-sections. Fig. IV is a perspective view of one-half of the central master-ring with a binding-wire associated therewith.

1 designates a piston-rod mounted in the packing-box 2, that is provided with a gland 3, held to the packing-box by bolts 4 in the usual manner.

5 designates outer sectional master-rings, each ring being preferably composed of two members that are held together by binding-wires 6. The master-rings 5 are situated at the ends of the packing on the piston-rod 1, and each of said rings is provided with an outer tapering face 7 and an inner tapering face 8 upon their inner sides.

9 is a central sectional master-ring, the sections of which are held together by a binding-wire 10. This central master-ring is provided upon both sides with outer inclined faces 11 and inner inclined faces 12. (See Figs. I and IV.)

13 designates sectional intermediate packing-rings each composed of a series of members, preferably three, that are held assem-

bled by winding-wires 14. Each packing-ring 13 is provided with a flat face 15, that is adapted to receive the mating packing-ring, as seen in Fig. I, and each of said rings is provided with a tapered face 16, that is 55 adapted to seat against the inclined inner face 8 of an outer master-ring or an inclined inner face 12 of the central master-ring which it opposes.

From the foregoing it will be seen that the 60 tapered faces 16 of the packing-rings 13 are securely held between the inclined faces 8 and 12 of the master-rings in pairs, so that each pair of packing-rings will be forced inwardly to the piston-rod by the master-rings 65 and held thereto by reason of the inclined contact between said parts. The arrangement of the master-rings with their inclined faces and the packing-rings between them, so that their tapered faces bear against the inner inclined faces of the master-rings, provides a socket-bearing between the parts that permits a freedom of movement of the packing-rings between the master-rings, whereby the packing-rings are held projected toward 75 the piston-rod with ease and certainty, so that they will constantly tend to approach the piston-rod both when the parts are originally assembled and also thereafter in the practical use of the packing.

17 designates pliable rings that are interposed between the master-rings and the packing-rings to occupy positions between the outer inclined faces of said master-rings and the coincident tapering faces of the packing-rings. These pliable rings permit a limited movement of the packing-rings 13 with respect to the master-rings between which they are situated, so that said packing-rings may partake of a rocking movement to a limited 85 degree to cause them to be constantly carried inwardly toward the piston-rod by the pressure of the master-rings thereagainst through the bearing provided by the inner inclined faces of the said rings.

I claim as my invention—

1. In a piston-rod packing, the combination of a series of master-rings having inner and outer inclined faces at their sides, and packing-rings situated between said master-rings 90

and having tapering faces adapted to bear against said inner inclined faces of the master-rings, substantially as described.

2. In a piston-rod packing, the combination of a series of master-rings having inner and outer inclined faces at their sides, packing-rings situated between said master-rings, and having tapering faces adapted to bear against said inner inclined faces of the master-rings, and pliable packing-rings arranged between the outer inclined faces of said master-rings and said packing-rings, substantially as described.

3. In a piston-rod packing, the combination

of a pair of outer master-rings having inclined faces upon their opposing sides, a central master-ring having an inner inclined face on each of its sides, and pairs of packing-rings situated between said outer master-rings and said central master-ring, said packing-rings having tapered faces adapted to bear against the inclined faces of said outer and central master-rings, substantially as described.

GEO. F. ALLEN.
